[57] CLAIM

The ornamental design for a telephone connector block, as shown and described.

DESCRIPTION

FIG. 1 is a side elevational view of a telephone connector block showing my new design;

FIG. 2 is a top plan view thereof;

FIG. 3 is an opposite side elevational view thereof;

FIG. 4 is a bottom plan view thereof;

FIG. 5 is a front elevational view thereof;

FIG. 6 is a rear elevational view thereof.

One of the component parts is shown in an alternate position in FIGS. 3-6 for purposes of disclosure only.

FIG. 3.

FIG. 2.

FIG. 1.

FIG. 4.

FIG. 5.
FIG. 6.
